DEEP WELL TURBINE PUMP HAVING SEPARATE MEANS FOR CARRYING HYDROSTATIC LOADS

Application filed July 26, 1926. Serial No. 124,858.

This invention has to do with a turbine pump which is designed for use in very deep wells.

Turbine pumps of the ordinary construction consist of a pump unit which is located near the bottom of a well and which is secured to a column or discharge pipe which extends to the surface of the ground. The pump unit comprises a number of pump bowls which provide runner chambers in which runners are situated. The runners are secured to a pump shaft which extends from the pump unit to the surface of the ground through the column pipe, the pump shaft being attached to a pump head by means of which it and the runners are rotated in such a manner as to pump liquid to the surface of the ground.

These pumps have been confined to use more or less on shallow wells while reciprocating pumps have been used on deep wells, which in the oil well industry are as deep as three or four thousand feet.

Probably the chief reason why the ordinary turbine pump cannot be used in deep wells is that difficulties arise by reason of the stretch in the pump shaft which extends from the pump unit to the pump head. The runners which revolve in the runner chambers formed by the pump bowls must be placed centrally in the runner chambers so that they will not engage either the upper or the lower walls thereof. In shallow pumps of a few hundred feet or so the stretch of the pump shaft is quite small and no difficulty is experienced. In deep wells, however, the stretch of the pump shaft would be considerable and the runners would not be properly positioned in the runner chambers. For example, in a deep well of say three thousand feet the stretch of the pump shaft, due to its own weight, would be about twelve or fourteen inches. Since the lower end of the pump shaft cannot move downwardly because of the runners there is a slack therein, and consequently the shaft is partially supported by the runners at the lower end thereof, whereas the pump shaft should be wholly supported at its upper end so that the run-

ners can be centrally placed in their respective runner chambers.

It is an object of my invention to provide a deep well turbine pump in which the runners may be correctly positioned in the runner chambers regardless of the depth of the pump.

A further object of my invention is to provide a deep well turbine pump in which the runners are supported by means wholly separate from the means supporting the pump shaft.

In my invention I employ what I term a runner shaft which extends only through the pump unit and to which the runners are rigidly secured. The runner shaft is supported by means of a thrust bearing which is preferably placed at the lower end thereof. Extending from the upper end of the runner shaft to the surface of the ground is the pump shaft which is supported by a bearing at the upper end of the well. The pump shaft and the runner shaft are drivably connected together, but the connection permits a relative vertical movement between these two parts. After the pump has been installed in the well, the upper end of the pump shaft may be moved upwardly so that the slack will be removed therefrom and so that it will be supported wholly by the bearing at the upper end of the well. It is essential that the one making the adjustments know when all the slack is removed from the pump shaft and when it is supported wholly at its upper end.

It is therefore an object of this invention to provide a deep well turbine pump having means for determining when the pump shaft is supported entirely from its upper end.

Still another object of this invention lies in a novel manipulative method of assembling and adjusting a turbine pump.

Still other objects of my invention lie in the particular details of construction whether or not these are used in combination with a turbine pump.

Other objects and advantages of the invention will be made evident hereinafter.

Referring to the two drawings in which I illustrate a preferred form of my invention,

Fig. 1 is a vertical section through the upper end of the pump of my invention.

Fig. 2 is a vertical section through the lower end of the pump of my invention, this view showing the parts in correct operating position.

Fig. 3 is a section similar to Fig. 2 but showing the parts in position previous to adjusting them into operating position.

10 Fig. 4 is a section taken on the line 4—4 of Fig. 1.

Fig. 5 is a section taken on the line 5—5 of Fig. 2.

15 The form of my invention shown in the drawings consists of a pump unit 11 (Figs. 2 and 3) which is situated at the lower end of a column pipe 12 inside a well casing 13. The pump unit 11 consists of an upper section 15 and a lower section 16, between which 20 pump bowls 17 are located. These sections and bowls are secured together as illustrated in Figs. 2 and 3. The pump unit 11 is secured to the lower end of the column pipe 12 by means of a screw joint as indicated at 18. 25 The upper end of the column pipe 12 is secured to a sub-flange 19 which supports a body 20 of a pump head, this pump head being situated at the surface of the ground.

30 Referring particularly to Figs. 2 and 3 the upper section 15 has passages 22 formed therethrough, the upper ends of which connect to the interior of the column pipe 12. The pump bowls 17 have passages 23, the lower ends of which connect to the runner chambers 24 formed near the lower parts of each bowl 17. The upper ends of the passages 23 of the upper bowl 17 connect to the lower ends of the passages 22 of the upper section 15 and the upper ends of the passages 23 of 40 the other pump bowl 17 connect to the runner chambers 24. The lowermost runner chamber 24 is connected by a mouth 25 to a space 26 of the bottom member 16. This space 26 is provided by an annular wall 28 having perforations 29 therein. Surrounding the bottom member 16 and extending downwardly therefrom is a screen pipe 30. Oil to pass into the pump unit 11 must pass through the screen pipe 30 through the perforations in the wall 50 28 and may then pass into the lower runner chamber 24.

55 Situated in each runner chamber 24 is a runner 32 having passages 33 formed therethrough. The upper and lower ends of the passages 33 connect with the passages 23 of adjacent pump bowls 17.

60 Extending through the pump unit 11 is a runner shaft 36 which is rotatably supported by the bearings of the upper and lower sections 15 and 16 and the pump bowl 17, such as illustrated clearly in Figs. 2 and 3. The runners 32 are rigidly secured on the runner shaft 36 by keys 37. The lower end of the bottom member 16 is provided in the form of 65 a bearing chamber 38 into which the lower

end of the runner shaft 36 extends. The lower end of the runner shaft 36 is reduced as indicated at 40 so as to provide an annular shoulder 41 which is engaged by a thrust plate 42. A spacer ring 43 is attached to the lower part of the thrust plate 42 by pins 44. The lower part of the spacer ring 43 engages an upper race of a runner shaft supporting bearing 46 which is supported by a radial wall 47 formed at the lower end of the bearing chamber 38. This bearing 46 supports the weight of the runner shaft 36 and the runners 32, and it also takes the hydraulic thrust imposed on the runners, as will be hereinafter described, while the pump is in operation.

70 A main bearing 50 is threadedly secured at 51 to the upper end of a hub 52 of the upper section 15. This main bearing 50 surrounds the upper end of the runner shaft 36 and provides a journal therefor. A tube 53 is threadedly secured at 54 to the main bearing 50. The upper end of the tube 53 has a collar 55 secured thereto which surrounds the lower end of a pump shaft 56 which extends downwardly into the interior of the tube 53, the collar 55 forming a bearing for this pump shaft 56. The upper end of the runner shaft 36 is provided with grooves 58, as illustrated clearly in Fig. 5. Threadedly secured at 59 to the lower end of the pump shaft 56 is a coupling member 60. This coupling member 60 is provided with a cavity 61 into which the upper end of the runner shaft 36 may extend. The coupling member 60 is provided with splines 63 which extend into the cavity 61 and the inner parts thereof are adapted to rest in the grooves 58 formed in the upper end of the runner shaft 36. This construction provides a driving connection between the runner shaft 36 and the pump shaft 56, but permits relative vertical movement therebetween. The pump shaft 56 extends upwardly through the column pipe 12 to the surface of the ground. The extreme upper end thereof projects through a stuffing box 65 and terminates at a point directly above the body 20 of the pump head. A flanged member 66 of a flexible coupling 67 is threadedly secured at 68 to the upper end of the pump shaft 56 as illustrated in Fig. 1. Surrounding the upper end of the pump shaft 56 is a pump shaft thrust bearing 69, the upper race 70 of which is engaged by a lower face 71 of the flanged member 66. A lower race 72 of the bearing 69 is supported by a diaphragm 73 which is extended across the upper end of a box 74 of a weighing device 75. The diaphragm 73 is secured in place by securing rings 76 and 77. The box 74 provides a closed annular chamber 79 in which a non-compressible fluid is placed. 120 A gauge 80 for the purpose of indicating the pressure of the non-compressible fluid is connected to the closed chamber 79 by means of a pipe 81.

125 It is apparent from Fig. 1 that the thrust

bearing 69 is provided for the purpose of supporting the weight of the pump shaft 56. The pump shaft 56 is driven by a motor 83 which is supported above the body 20 by means of a frame 84. A motor shaft 85 of the motor 83 extends downwardly to a point above the upper end of the pump shaft 56 and is provided with a flange member 86 which forms a part of the flexible coupling 67. The flanged members 66 and 86 are drivably connected together in any well known manner so that the motor shaft 85 is drivably connected to the pump shaft 56.

In Figs. 1 and 2, I illustrate the parts of the pump in the positions which they will occupy when the pump is adjusted for operation. In Fig. 3 I represent the positions of the parts before they have been adjusted. As previously explained, in extremely deep wells the stretch in the pump shaft is considerable and this shaft will have a great amount of slack therein. When all the parts have been installed with the exception of the motor 83 and the upper flanged member 86, there will be a stretch in the pump shaft 56 and the lower end of the coupling member 60 will be in engagement with the upper end of the main bearing 50. It will be recognized that for this reason the pump shaft will not be entirely supported from the pump shaft thrust bearing 69 but it will be partially supported at its lower end by the main bearing 50. Before the pump can be set into operation this slack must be removed and the removal of the slack is accomplished in the following manner:

The flanged member 66 is turned relatively to the pump shaft 56 so that the upper end of the pump shaft 56 will be advanced upwardly. As the pump shaft 56 is pulled upwardly, more of the weight thereof will be carried by the bearing 69. Consequently the non-compressible fluid in the chamber 79 will have a greater pressure exerted thereon which will be indicated by the gauge 80. The pressure indicated by the gauge 80 will increase until all of the weight is carried by the bearing 69, that is to say, it will increase until the coupling member 60 disengages from the bearing 50. When this movement has been effected, all of the weight of the pump shaft 56 will be carried by the bearing 69, and therefore any upward movement of the pump shaft thereafter will not place any additional weight on the bearing 69 or any additional pressure on the non-compressible fluid in the chamber 79. The person making the adjustments will therefore watch the gauge 80 and will lift the pump shaft as long as the pressure increases thereon. When the pump shaft is raised to the extent that disengagement of the coupling member 60 and the main bearing 50 has been brought to pass, the gauge pressure will not increase and the operator will be informed that the

pump shaft is wholly supported at its upper end. It is desirable, however, to lift the pump shaft an inch or two farther than this so that there will be plenty of clearance between the coupling member 60 and the main bearing 50.

My invention also provides a means for preventing the pump shaft from being moved too high so that there would be a disconnection between the pump shaft and the runner shaft. Referring to Fig. 2, it will be seen that if the pump shaft is lifted above a certain point the upper face of the coupling member 60 will engage the lower face of the collar 55. This will prevent an upward movement of the lower end of the pump shaft 56 and obviously a sudden increase of pressure will be placed on the non-compressible fluid in the chamber 79 which will be indicated by the gauge 80. This sudden increase in pressure as indicated by the gauge 80 will inform the operator that the coupling member 60 has moved into engagement with the collar 55 and he may then lower the pump shaft to position the coupling member 60 in a proper place.

From the foregoing description it will be seen that my invention differs materially from the ordinary turbine pump inasmuch as I provide two shafts, that is, the runner shaft 36 and the pump shaft 56, which are drivably connected together in place of providing a unitary pump shaft according to standard practice. Also the runner shaft 56 is supported by the runner shaft thrust bearing 46 which is entirely separated from the pump shaft thrust bearing 69. After the pump has been adjusted, as just described, the motor 83 is energized and the pump is set into operation. As the pump accelerates to full speed, hydraulic thrust is imposed on the runners 32 which exerts a down pressure thereon. By reason of the fact that the bearing 46 is so close to the runners 32 there will be no "give" in the runner shaft 36 and therefore the runners 32 will not move from central position in the runner chambers 24; therefore, there will be no engagement of the runners as would be present in the ordinary form of turbine pump which would be supported from the upper end of the pump shaft. The bearing 46 operates in a bath of lubricating oil which is placed in the bearing chamber 36. It should also be noted that the chamber 38 is in such a position that the oil or other fluid entering the pump passes therewith and keeps it cool.

I claim as my invention:

1. A turbine pump comprising: a pump unit adapted to be placed in a well; means for supporting said pump unit; a runner situated in a runner chamber of said pump unit; a runner shaft having said runner secured thereto; means for supporting said runner shaft; a pump shaft extending from

said runner shaft to the upper end of said well; means for supporting said pump shaft; means for rotating said pump shaft; means for drivably connecting said pump shaft and said runner shaft together, said pump shaft being movable in a vertical direction relative to said runner shaft; means for moving said pump shaft in a vertical direction in order that it can be supported by said means for supporting said pump shaft; and means for determining when said pump shaft has been lifted sufficiently for same to be supported by said means for supporting said pump shaft.

13. 2. A turbine pump comprising: a pump unit adapted to be placed in a well; means for supporting said pump unit; a runner situated in a runner chamber of said pump unit; a runner shaft having said runner secured thereto; a bearing situated adjacent to the lower end of said runner shaft for supporting said runner shaft; a pump shaft extending from said runner shaft to the upper end of said well; means for supporting said pump shaft; means for rotating said pump shaft; means for drivably connecting said pump shaft and said runner shaft together, said pump shaft being movable in a vertical direction relative to said runner shaft; means for moving said pump shaft in a vertical direction in order that it can be supported by said means for supporting said pump shaft; and means for determining when said pump shaft has been lifted sufficiently for same to be supported by said means for supporting said pump shaft.

3. A turbine pump comprising: a pump unit adapted to be placed in a well; means for supporting said pump unit; a runner situated in a runner chamber of said pump unit; a runner shaft having said runner secured thereto; a bearing situated adjacent to the lower end of said runner shaft for supporting said runner shaft; a pump shaft extending from said runner shaft to the upper end of said well; means for supporting said pump shaft; means for rotating said pump shaft; means for drivably connecting said pump shaft and said runner shaft together, said pump shaft being movable in a vertical direction relative to said runner shaft; means for moving said pump shaft in a vertical direction in order that it can be supported by said means for supporting said pump shaft; and a weighing device for determining when said pump shaft has been lifted sufficiently for same to be supported by said means for supporting said pump shaft.

4. A turbine pump comprising: a pump unit adapted to be placed in a well; means for supporting said pump unit; a runner situated in a runner chamber of said pump unit; a runner shaft having said runner secured thereto; means for supporting said runner shaft; a pump shaft extending from said run-

ner shaft to the upper end of said well; means for supporting said pump shaft; means for rotating said pump shaft; means for drivably connecting said pump shaft and said runner shaft together, said pump shaft being movable in a vertical direction relative to said runner shaft; means for moving said pump shaft in a vertical direction in order that it can be supported by said means for supporting said pump shaft; means for determining when said pump shaft has been lifted sufficiently for same to be supported by said means for supporting said pump shaft; and means engageable with said means for drivably connecting said shafts for preventing said pump shaft from being lifted enough to disconnect it from said runner shaft.

5. A turbine pump comprising: a pump unit adapted to be placed in a well; means for supporting said pump unit; a runner situated in a runner chamber of said pump unit; a runner shaft having said runner secured thereto; a bearing situated adjacent to the lower end of said runner shaft for supporting said runner shaft; a pump shaft extending from said runner shaft to the upper end of said well; means for supporting said pump shaft; means for rotating said pump shaft; connecting means for drivably connecting said pump shaft and said runner shaft together, said pump shaft being movable in a vertical direction relative to said runner shaft; means for moving said pump shaft in a vertical direction in order that it can be supported by said means for supporting said pump shaft; means for determining when said pump shaft has been lifted sufficiently for same to be supported by said means for supporting said pump shaft; and a collar above said connecting means for preventing said pump shaft from being lifted enough to disconnect it from said runner shaft.

6. A turbine pump comprising: a pump unit; a runner situated in a runner chamber of said pump unit; a runner shaft having said runner secured thereto; a bearing adapted to support said runner shaft, said bearing being adapted to take the hydraulic thrust of said runner; a pump shaft axially slidable relative to said runner shaft, said pump shaft driving said runner shaft; an upper bearing on said pump shaft for carrying the weight thereof; means for raising said pump shaft until said upper bearing supports the weight of said pump shaft; and means for indicating when no axial thrust is present between said pump shaft and said runner shaft.

7. A turbine pump comprising: a pump unit; a runner situated in a runner chamber of said pump unit; a runner shaft having said runner secured thereto; a bearing adapted to support said runner shaft, said bearing being adapted to take the hydraulic thrust of said runner; a pump shaft axially slidable

- relative to said runner shaft, said pump shaft driving said runner shaft; an upper bearing on said pump shaft for carrying the weight thereof; means for raising said pump shaft 5 until said upper bearing supports the weight of said pump shaft; and a weighing device for indicating when said pump shaft is completely supported by said upper bearing.
8. In a turbine pump, the combination of: 10 a pump unit situated in a well; a pump shaft extending into said well and resting against a portion of said pump unit when said pump unit has been first installed; means for raising the upper end of said shaft; and means 15 for determining when the stretch is out of said shaft and the lower end thereof rises from contact with said portion of said pump unit.
9. In a turbine pump, the combination of: 20 a pump unit situated in a well; a pump shaft extending into said well; a member secured to the lower end of said pump shaft, said member being axially movable a predetermined maximum distance but normally resting 25 on a portion of said pump unit when said pump unit has been first installed; means for raising the upper end of said shaft; and means operable when said pump shaft is stationary for determining when said member 30 is raised from its resting position.
10. In a turbine pump, the combination of: 35 a pump unit situated in a well; a pump shaft extending into said well; a member secured to the lower end of said pump shaft, said member being axially movable a predetermined maximum distance but normally resting 40 on a portion of said pump unit; means for raising the upper end of said shaft; and a weighing device for determining when said member is raised from its resting position.
11. In a turbine pump, the combination of: 45 a pump unit situated in a well; a pump shaft extending into said well; a member secured to the lower end of said pump shaft, said member being axially movable a predetermined maximum distance but normally resting 50 on a portion of said pump unit; means for raising the upper end of said shaft; and hydraulic means operable when said pump shaft is stationary for determining when said member is raised from its resting position.
12. A turbine pump, comprising: a pump unit; a runner in said pump unit; a runner shaft having said runner secured thereto; 55 means for supporting said runner shaft; a pump shaft axially movable relative to said runner shaft and being operatively connected thereto, said pump shaft being supported at 60 its lower end during the installation of said pump; an upper bearing for said pump shaft; a fluid-supported diaphragm supporting said upper bearing; means for drawing upward on said shaft relative to said bearing 65 whereby the weight supported by said upper bearing successively increases while the slack is being removed from said pump shaft; and means for indicating the amount of pressure on the fluid supporting said diaphragm to indicate the successively increasing weight supported by said upper bearing during the time that the stretch is being removed from said pump shaft, said means showing no increasing weight when said pump shaft is drawn upward after the slack has been removed therefrom. 70
13. A method of assembling and adjusting a turbine pump having a runner shaft and a line shaft operatively connected together but axially movable relative to each other, said runner shaft being supported independently of said line shaft, which method includes the use of a weighing means supporting said line shaft and includes the following steps: ascertaining the weight of said line shaft; lowering the pump into a well; drawing upward on the upper end of the line shaft whereby said weighing means indicates the weight of that portion of the line shaft supported thereby; and noting the reading of said weighing means to determine when the weight of said line shaft is entirely supported thereby. 80
14. In a turbine pump, the combination of: a pump unit supported in a well; a relatively 85 long shaft extending into said well to operate said pump unit; means for moving upward on the upper end of said shaft, no upward movement of the lower end thereof taking place until the stretch is out of said shaft; and means at the top of said well for indicating when the lower end of said shaft moves upward thus indicating that the stretch has 90 been removed from said shaft. 95
- In testimony whereof, I have hereunto set 100 my hand at Los Angeles, California, this 15th day of July, 1926.
